Primary Examiner — Karen Kearney*Assistant Examiner* — Debra Callahan(74) *Attorney, Agent, or Firm* — Patent Law Works LLP(57) **CLAIM**

The ornamental design for a display screen or portion thereof with a graphical user interface, as shown and described.

DESCRIPTION

The FIGURE is a front view of a display screen or portion thereof with a graphical user interface showing the new design.

The outermost broken lines illustrate the display screen or portion thereof and form no part of the claimed design. The remaining evenly spaced broken lines and the diagonal broken lines illustrate portions of the graphical user interface and form no part of the claimed design.

1 Claim, 1 Drawing Sheet(56)
